(57) **CLAIM**

The ornamental design for a wireless charger, as shown and described.

DESCRIPTION

FIG. 1 is a front perspective view of a wireless charger according to the invention.

FIG. 2 is a front view of the wireless charger of FIG. 1.

FIG. 3 is a rear view of the wireless charger of FIG. 1.

FIG. 4 is a left side view of the wireless charger of FIG. 1.

FIG. 5 is a right side view of the wireless charger of FIG. 1.

FIG. 6 is a top plan view of the wireless charger of FIG. 1.

FIG. 7 is a bottom plan view of the wireless charger of FIG. 1; and,

FIG. 8 is a rear perspective view of the wireless charger of FIG. 1.

The broken lines in the figures depict portions of the article which form no part of the claimed design.
